(57) **CLAIM**

The ornamental design for an engine hood of an agricultural vehicle, substantially as shown and described.

DESCRIPTION

FIG. 1 is a perspective view of an engine hood of an agricultural vehicle having a plurality of panels in a closed position;

FIG. 2 is a perspective view of the engine hood with the plurality of panels in an open position;

FIG. 3 is a front view of the engine hood with the plurality of panels in the open position;

FIG. 4 is a back view of the engine hood with the plurality of panels in the open position;

FIG. 5 is a top view of the engine hood with the plurality of panels in the open position; and,

FIG. 6 is a bottom view of the engine hood with the plurality of panels in the open position.

Phantom lines, where utilized, are for illustrative purposes only and form no part of the claimed design.

1 Claim, 5 Drawing Sheets
